UNITED STATES PATENT OFFICE

155,507

DESIGN FOR A PHOTOGRAPHIC EXPOSING, DEVELOPING, AND PRINTING APPARATUS

David D. Hatfield, Los Angeles, Calif., assignor to
Dansee Corporation, Santa Monica, Calif., a
corporation of California

Application June 30, 1947, Serial No. 140,009

Term of patent 3½ years

(Cl. D61—1)

To all whom it may concern:

Be it known that I, David D. Hatfield, a citizen of the United States, residing at Los Angeles, in the county of Los Angeles, State of California, have invented a new, original, and ornamental Design for Photographic Exposing, Developing, and Printing Apparatus, of which the following is a specification, reference being had to the accompanying drawing, forming part thereof, in which:

Fig. 1 is a top perspective view taken from one side and one end of the photographic exposing, developing, and printing apparatus, showing my new design;

Fig. 2 is a top perspective view taken from the opposite side and end of the photographic apparatus as shown in Fig. 1; and

Fig. 3 is a bottom plan view thereof.

I claim:

The ornamental design for a photographic exposing, developing, and printing apparatus, substantially as shown.

DAVID D. HATFIELD.
